UNITED STATES PATENT OFFICE.

SOLOMON S. BENSTER, OF TOLEDO, OHIO.

ATTACHMENT FOR CAMERAS.

SPECIFICATION forming part of Letters Patent No. 339,731, dated April 13, 1886.

Application filed June 4, 1885. Serial No. 167,592. (No model.)

To all whom it may concern:

Be it known that I, SOLOMON S. BENSTER, of Toledo, in the county of Lucas and State of Ohio, have invented new and useful Improvements in Attachments to Cameras; and I do hereby declare that the following is a full, clear, and exact description thereof, reference being had to the accompanying drawings, which form a part of this specification.

This invention relates to certain new and novel improvements in attachments to cameras; and the object of the invention is to construct a device to be attached to the lens-tube of a camera, and adapted to serve the double purpose of diaphragm and shutter; and the invention consists in the peculiar construction, arrangement, and operation of suitable wings situated within the lens-tube, and adapted to be instantaneously opened and closed at the will of the operator, such opening and closing of the wings being from and to the central focusing of the lens or lens-tube; secondly, in the peculiar construction and arrangement of devices for instantaneously operating these shutters or wings; and, thirdly, in the peculiar construction, arrangement, and combinations of the various parts, all as more fully hereinafter set forth.

Figure 1 is a cross-section through the lens-tube of a camera immediately in front of the diaphragm, and showing my improved device in place and as closed. Fig. 2 is a perspective view of the diaphragm with the wings partially opened. Fig. 3 is a detached elevation of the cam-ring with all but two of the wings removed. Fig. 4 is a longitudinal section on the line $x-x$ in Fig. 1. Fig. 5 is a perspective view of the lens-tube. Fig. 6 is a cross-section of the ring which forms a part of the diaphragm, showing the means for securing it to the inner tube.

In the accompanying drawings, which form a part of this specification, A represents the outer tube, which is provided with the flange B, by means of which it is secured to the camera-box as in the ordinary manner, and C is the inner or slide tube, which is provided with the ordinary means for sliding it in or out of the stationary tube A; but as this forms no part of my invention, I neither show it in my drawings nor enter into a description of its construction.

Within the slide-tube C, I secure the usual

flange, D, immediately in front of which is cut through the wall of the slide-tube a slot, a, 55 while in the outer tube a square portion is cut away, so that the inner tube may be adjusted in or out as the operator may desire.

E is an annular ring slightly smaller in diameter than the internal diameter of the sliding tube C, and in the periphery of this ring E there is formed a groove, b, which, when the ring is in place within the tube, comes coincident with the slot a through the wall of such tube. In the front face of this ring E there is 60 formed an annular depression, c, adapted to receive the oscillating cam-ring F, which is provided with an arm, G, which projects outwardly through the groove b of the ring E and the slot a of the tube C. 70

H is a plate, which is inserted through the so called "diaphragm-slot" a into the groove b of the ring E, and is secured thereto by suitable pins, d, and I is a key or wedge, which is inserted through a proper key-hole, i, in the plate H adjacent to the outer wall of the inner tube, so as to draw the ring E tightly and rigidly against the inner wall of the tube, preventing thereby its accidental displacement. This plate H is provided with a curved index-arm, J, the free end of which rests against the outer wall of the inner tube. 80

K represents a cylinder closed at one end and secured to the plate H. Within this cylinder is placed a proper piston, the piston-rod L of which extends down to and through the inwardly-projecting portion of the arm J, and the lower or outer end of this piston-rod is threaded and carries upon it a thumb-nut, M, which regulates the throw of the piston, 90 as hereinafter described.

N is a nipple, which communicates with the interior of the cylinder K through its head, as shown, and is adapted to receive one end of a flexible tube, the other end of which carries a bulb or other suitable device, by means of which air may be forced into the cylinder to cause the outward stroke of the piston, and which will, on releasing the bulb, cause the piston to resume its original position by suction. The arm G of the oscillating cam-ring E is passed through the slot g in the piston-rod L. In Fig. 1 it is shown connected; but in Fig. 2 these parts are shown detached, to better illustrate the slot. 95 100 105

O represents a series of wings or shutters,

substantially of the form shown, the outer ends of which are pivotally secured to the annular ring E, while pins e project downwardly from the rear faces of these wings O, 5 to engage with the slots h upon the inner edge of the ring F, as shown. These wings, as will be seen upon reference to the drawings, overlap each other, and when in their closed position, as shown in Fig. 1, form for, all practical 10 purposes, a completely closed diaphragm, shutting out entirely the passage of any rays of light through the tubes.

In taking instantaneous photographs with the ordinary apparatus provided therefor 15 the work produced has a flat appearance, as in an open lens with diaphragm removed, the outlines or features not standing out sharp, and those portions not directly under the focus of the lens appear smoky and 20 blurred; and it is one of the objects of this invention to overcome this great objection in instantaneous photography, while at the same time the employment of different sizes of diaphragms to produce a difference in the depth 25 and sharpness of pictures taken is avoided; and the operation of my device is as follows: The operator sits or places the subject in a proper position before the camera and then arranges his focus through the camera, as in 30 the ordinary manner; but as the normal position of my device is always closed, as shown in Fig. 1, the operator must, by squeezing the bulb, force air into the cylinder and project its piston-rod until the thumb-nut M strikes 35 against the inwardly-bent portion of the arm J. In this movement of the piston and its rod and by its connection with the arm G of the ring F such ring is compelled to partially turn or oscillate in its bearing in the ring E, 40 causing the pins e of the wings O to slide up in the slots h and throw such wings radially from the center to the periphery of the ring E, leaving the sight free and unobstructed through the lens-tubes to their fullest capacity. Having adjusted the focus, the operator releases the bulb, which, refilling with air 45 by suction, draws the piston back into its original position, compelling, by the connections herein named, the wings O to assume their normal or closed position, shutting out and preventing the passage of rays of light through the tubes. The operator now inserts the chemical plate, which has previously been prepared, 50 in its proper receptacle in the camera-box, when he again quickly presses the bulb and as quickly releases it, compelling, as hereinbefore described, the wings O to instantaneously open and close, and while this is being done by such wings the reflection of the subject has been 55 cast and made upon the chemical plate. Now, it will be observed that as these wings open from the center to the periphery the first ray 60 of light that passes through the infinitesimal opening that may be made must necessarily throw the entire reflection of the subject

upon the chemical plate, making and producing a negative which is sharp and bold in all of its outlines and features, and which may be said to stand out bodily from the chemical plate upon which the object is reflected, while, 7c as the wings open still farther to their greatest extent, the diffusion of the rays upon the negative produces a softening and brilliancy of lines and shadows, and as the wings assume their normal or closed position the rays of light are again concentrated to the center, and the focus gives additional boldness to the lines. It will be observed that the wings O being pivotally secured to a ring upon lines radiating from a common center the same are 80 caused to move outwardly from such common center to the periphery of the ring to which they are attached. The opening formed is circular, or as nearly so as can be formed by a series of plates arranged to enlarge or diminish the area of the circular opening made or formed by them in their various positions.

While I have described in connection with this device a cylinder adapted to be operated by the compression and suction of air, I do 90 not desire to confine myself strictly to such construction, as there are undoubtedly various other means which could be employed for causing an instantaneous opening and closing of the wings of the diaphragm. If the operator 95 should desire to restrict the opening of the wings of the diaphragm, so as to have a greater concentration of the rays, he can run the nut M down upon the thread of the piston-rod, so as to shorten the distance between 100 such nut and the arm J, and thus limit the throw of the piston, which must necessarily limit the movements of the wings.

What I claim as my invention is—

1. In combination with the lens-tubes of a 105 photographing - camera, a combined shutter and diaphragm, consisting of the ring E, cam-ring F, and wings O, when constructed, arranged, and operating substantially in the manner and for the purposes set forth.

2. In combination, the lens-tubes B C, provided with a combined shutter and diaphragm constructed substantially as described, the cylinder K, provided with a piston and piston-rod, L, arranged to be projected and 115 retracted instantaneously, and connected to the oscillating cam - ring F, substantially as and for the purposes specified.

3. In a device for the purpose described, the combination, with a combined shutter and diaphragm, and a piston and piston-rod arranged to be projected and retracted instantaneously, of the nut M upon the threaded end of said piston - rod, and constructed to limit the size of the diaphragm-opening, as set 125 forth.

SOLOMON S. BENSTER.
